TOOTH BRUSH STERILIZER

Raymond F. Curiel, 3041 N. Inyo St., Bakersfield, Calif.

Filed Mar. 2, 1965, Ser. No. 84,040

Term of patent 14 years

(Cl. D83—1)

FIG. 1 is a top plan view of the tooth brush sterilizer embodying my new design;

FIG. 2 is a side elevational view of the same;

FIG. 3 is a bottom plan view of the same.

I claim:

The ornamental design for a tooth brush sterilizer, as shown.
